Primary Examiner — Nathan M Johnston

(74) *Attorney, Agent, or Firm* — S.J. Intellectual Property LTD.

(57) **CLAIM**

The ornamental design for a splash guard, as shown and described.

DESCRIPTION

FIG. 1 is a front, right and top perspective view of a splash guard, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right and top perspective view thereof, shown in a state of use; and,

FIG. 10 is a rear, left and bottom perspective view thereof, shown in a state of use.
The broken lines in the drawings depict portions of the splash guard that form no part of the claimed design. The additional broken lines showing of a bathtub in FIGS. 9 and 10 depict environmental structure that form no part of the claimed design.

1 Claim, 10 Drawing Sheets
